DESK LAMP

Fred Craib, Martinez, Calif.

Application March 23, 1938, Serial No. 197,649

3 Claims. (Cl. 240—81)

My invention refers to reading lamps and more particularly to a reading lamp having a circular reflector with auxiliary means for producing an asymmetrical light pattern therefrom.

Symmetrical reading lamps having a central upright lamp support and a circular reflector mounted thereon are often used for desks and the like and the lamp is usually positioned on one side of the desk. Much of the light emitted by the lamp is, therefore, not utilized, being dispersed over the edge of the desk.

15 The main object of my invention is to provide a reading lamp having a conical reflector mounted on a central support wherein an asymmetrical light pattern is obtained, whereby the light may be projected across the desk and whereby a greater portion of the light emitted by the lamp is utilized.

20 Other objects of my invention will be apparent or will be specifically pointed out in the description forming a part of this specification, but I do not limit myself to the embodiment of the invention herein described, as various forms may be adopted within the scope of the claims.

28 Other broad objects of my invention may be more fully understood by direct reference to the drawings, wherein:

Figure 1 is a longitudinal sectional view, having portions thereof in elevation, of a reading lamp embodying my invention.

Figure 2 is a partial sectional view, partly in elevation and partly in section, of another modification of my invention.

38 Figure 3 is a perspective view looking down on the top of the lamp shown in Figure 2 with the reflector removed.

40 Referring directly to the drawings:
In Figure 1 a lamp base 1 is provided in the usual manner with a base collar 2 and a central standard 3, held together as is customary in the art by a central hollow rod 4 fastened to the base 1 by nut 5. The upper end of rod 4 is provided with an upper nut 6, supporting a lamp sleeve 7 and a lamp socket 8 inside sleeve 7. The customary incandescent lamp 9 is positioned in socket 8.

Clamped between sleeve 7 and central standard 3 is a bracket 10 extending laterally and upwardly to avoid the lamp. The bracket 10 carries an arm 11, removably affixed thereto and locked by means of a thumb screw 12 and maintained from turning by bracket pin 12'. The arm 11 is bent toward the axis of the lamp and terminates in a screw 14, positioned in line with the axis of central standard 3.

The screw 14 has placed thereover a main reflector 15, which is roughly conical and has a circular rim, thus making the entire reflector 15 concentric with central standard 3 and base 1. The reflector 15 is held by a nut 16.

I prefer to drop rim 17 of main reflector 15 below the open end 19 of sleeve 7, in order that the user of the desk may not see the lamp directly.

1887. Considering the structure so far described, the lamp in use would have a symmetrical light pattern and, if the lamp were to be used on the edge of a desk, for example, a portion of the light away from the user of the desk would be wasted. In order to prevent such waste of light, I provide, immediately around lamp 9, an auxiliary reflector 20 placed to one side of the lamp and directing light to the opposite side of reflector 15, the axis of the auxiliary reflector and of the light beam projected thereby being substantially parallel to the slope of the main reflector. Thus the maximum of light may be directed toward the person using the desk and across the desk surface. 10 15 20

In the modification shown in Figure 2, I utilize 25
two lamps. Here the central rod 4 is extended
upwardly along the axis of the central column
3 and terminates in a screw 14, and reflector 15 is
mounted directly on this screw. No lamp bracket
10 is needed, but in this case two arms 21 are pro-
vided extending from central rod 4 and supporting
auxiliary reflectors 22. In this case the angle
30 of the auxiliary reflector is made the same
as when a single reflector is utilized. Sleeves 7
are placed on an angle and mounted on a sleeve
tube 24, forming a continuation of the central
35 standard 3.

As is customary in the art, a hickey 26 is positioned at this point, in order to allow distribution of lamp wires 25. In like manner the base of central rod 4 is provided with a basal hickey 21, and the lamp wires 25 run through the central rod 4, to emerge through basal hickey 21, pass to switch 28, and thence to lamp cord 29.

The lamps are easily replaced: In the case of the modification in Figure 1, thumb screw lock 12 is removed, thus allowing removal of the arm 11. Lamp bulb 9 may then be removed or replaced and the arm 11 be replaced in proper position. 45 50

In the modification shown in Figures 2 and 3, removal or replacement of bulbs 9 is easily accomplished by making the arms 21 of resilient material. Reflectors 22 may, therefore, be 55

pushed out of the way against resiliency of arms 21 to allow replacement of bulbs 9.

It will thus be seen that I have provided in very simple form a reading lamp which is to all 5 appearances symmetrical and yet which will give, due to the presence of auxiliary reflectors, an asymmetrical light pattern, thus providing a lamp which looks like the ordinary reading lamp but which has a light pattern ideally suitable for 10 desk use.

I claim:

1. A reading lamp or the like comprising a base, an upright extending from said base and terminating in an open sleeve, a lamp socket in 15 said open sleeve, a lamp in said socket, a reflector support extending upwardly from said upright below said lamp socket and including a detachable section extending upwardly around said lamp to terminate above said lamp in line with the axis of said upright, a substantially conical main reflector centrally mounted on the terminus of the detachable section of said reflector support and extending downwardly around said lamp with the rim of said reflector being below the level of the 20 open end of said sleeve, and an auxiliary reflector 25 attached to said detachable section of said reflector support at a point intermediate the ends thereof and partially surrounding said lamp and with the axis of said auxiliary reflector substantially parallel with the slope of the main reflector.

2. A reading lamp or the like comprising a base, an upright extending from said base and terminating in an open sleeve, a lamp socket in 5 said open sleeve, a lamp in said socket, a reflector support extending upwardly from said upright below said lamp socket and including a section detachably secured thereto by a thumbscrew and extending upwardly around said lamp to terminate above said lamp in line with the axis of 10 said upright, a substantially conical main reflector centrally mounted on the terminus of the detachable section of said reflector support and extending downwardly around said lamp with the rim of said reflector being below the level of the 15 open end of said sleeve, and an auxiliary reflector 20 attached to said detachable section of said reflector support at a point intermediate the ends thereof and partially surrounding said lamp and with the axis of said auxiliary reflector substantially parallel with the slope of the main reflector.

3. Apparatus as recited in claim 1 wherein the detachable section of the reflector support carrying the auxiliary and main reflectors is secured to the remainder of the support by a thumbscrew to facilitate lamp replacement, and is rigidly retained against turning by a pin secured to one of the portions of the reflector support and engaging the other portion.

FRED CRAIB.
